UNITED STATES PATENT OFFICE.

FRANK ENGEL AND JULIUS ENGEL, OF SYRACUSE, NEW YORK.

OIL BURNER.

Application filed May 27, 1926. Serial No. 112,105.

This invention appertains generally to new and useful improvements in burners and has more specific reference to a novel and simplified oil burner.

5 The primary object of the present invention is to provide such a burner of the nature stated including an inverted burner nozzle and a super-heater or generator whereby to insure a steadier and stronger flow of gas from 10 the burner nozzle, thereby eliminating the danger of blow backs.

A further object of the present invention is the provision of a new and novel type of burner nozzle.

15 Another object of the present invention is to provide such an improved burner of the nature stated having associated therewith safety means for automatically cutting off the supply of oil should the burner become 20 flooded due to the going out of the burner nozzle.

A still further object of the present invention is to provide such a burner of the nature stated which while simple in construction, 25 is nevertheless strong, sturdy and durable, one which is effective and efficient in its operation, one which can be manufactured and placed on the market at a reasonable figure and one which is well designed for the 30 purposes for which it is intended.

With these and numerous other objects in view, the invention resides in the novel construction, combination and arrangement of parts to be more fully hereinafter described, 35 illustrated in the accompanying drawings and particularly pointed out in the appended claims.

In the drawings forming a part of this application and wherein like characters of reference denote corresponding parts throughout the several views:

Figure 1 is a side view, partially in section, of an oil burner constructed in accordance with the present invention.

45 Figure 2 is a top plan view thereof.

Figure 3 is a sectional view taken on line 3-3 of Figure 1 looking in the direction of the arrows.

Figure 4 is a sectional view taken on line 50 4-4 of Figure 1 looking in the direction of the arrows.

Figure 5 is an enlarged detail sectional view of the burner nozzle.

Reference now being had more particularly to the accompanying drawings wherein

for the purpose of illustration has been disclosed a preferred embodiment of the present invention, the letter A generally indicates the present improved oil burner and B the safety means associated therewith for automatically cutting off the supply of oil thereto.

The burner A comprises in its construction a suitable base 10 from which rises the supporting standard 11 carrying intermediate its ends, a burner generally indicated by the numeral 12 and which may be of any conventional or preferred construction. The burner disclosed herein is of the Bunsen type and comprises a circular bottom wall 13 and 70 the annular flared side wall 14. Fitted within the burner 12 and spaced from the bottom wall 13 thereof to provide an oil chamber 15 is a block or plate 16 provided with the plurality of burner openings 17. Secured within the bottom wall 13 of the burner and communicating with the gas chamber 15 therein is one end of a gas pipe 18, said pipe being provided with a plurality of aligned lighting openings 19 and having its opposite 80 ends communicating with a suitable source of gas supply.

That portion of the standard 11 above the burner 12 is provided with a plurality of vertically disposed flutes 20 which provide flues 85 for the gas emitting from the burner 12. Mounted upon the upper end of the standard 11 is a hollow frusto-conical gas generator 21 adapted to be heated by means of the burner 12. Leading into one side of the generator 90 21 and communicating therewith is an oil supply pipe 22, the opposite end thereof communicating with a suitable oil containing tank or the like 23. Installed within the length of the oil supply pipe 22 is a suitable needle valve 24, the purpose of which will be set forth more fully hereinafter.

The generator 21 is provided at a point diametrically opposite the oil supply pipe 22 with the substantially vertically disposed gas 100 outlet pipe 26 which constitutes a super heater, the upper end of said pipe being curved inwardly and downwardly with the terminal 27 thereof positioned directly above the flues 20 and carrying the burner nozzle 28.

The burner nozzle 28 is of a novel construction and as disclosed to advantage in Figure 5, comprises a head 29 having a reduced nipple 30 which is threaded within the terminal 27 of the pipe 26, said nipple being formed 110

with the tip 31. Formed concentrically through the head 29, nipple 30 and tip 31 is a bore 32 which tapers from its inner to its outer end as clearly shown. The reduced tip 31 is provided to prevent the bore 32 from becoming clogged due to small particles in the oil or scale from the pipes. These small particles or scale will be collected in the space around the tip 31 and such particles and scale can then be readily removed by simply removing the burner nozzle. Thus, it will be seen that the burner nozzle will be effectively prevented from clogging and that the terminal of the gas outlet pipe 26 can be quickly and easily cleaned.

In order to operate the present improved oil burner the valve 24 is first opened to permit a small amount of oil to flow into the generator 21 after which the gas is turned 20 into the gas pipe 18 and lighted at the small hole 19. The flame will follow along the series of openings 19 until it reaches the burner 12 and lights the same. The heat from the burner 12 will heat the generator 25 21 converting the oil contained therein into a gas, this gas filling up the generator and finally passing upwardly through the gas outlet pipe 26. When the gas pressure is sufficient to emit at the burner nozzle 18, the 30 flame from the burner 12 coming up through the flues 20 will ignite the gas coming from said burner nozzle and the burner 12 should then be turned off. The flame from the burner nozzle 28 will be directed against the generator 21 which will cause the rapid generation of the gas therein. The flame after striking the generator 21 is deflected and this heat contacting with the gas outlet pipe 26 superheats the gas before it leaves the burner nozzle 28 thereby increasing the efficiency of the 40 said burner.

It will of course be understood that alcohol may be used instead of gas for starting the burner and when such alcohol is used, a sufficient amount of it is permitted to flow 45 through the pipe 18 until it reaches a predetermined level in the burner 12. The alcohol is then lighted and the subsequent operation is the same as has been outlined above.

50 The present invention also contemplates the provision of the novel means B for automatically stopping the flow of oil to the generator 21 should the same become flooded due to the momentary interruption in the oil supply and the going out of the burner nozzle. Such means embodies a solenoid 33 mounted upon the oil supply pipe 22 through the medium of a suitable bracket 34. The 55 solenoid 33 is provided with a slidable plunger 35 pivotally connected as at 36 to the needle valve operating arm 37. Leading from the solenoid 33 are the wires 38 and 39, the former being suitably secured within the burner plate 16 in the burner 12 while the wire 39 runs to 60 65 and is connected with a battery 40. Lead-

ing from the other terminal of the battery 40 is a wire 41, the opposite end thereof being also secured within the burner plate 16 of the burner 12. Thus, it will be readily appreciated that in case the burner nozzle 28 70 goes out due to a momentary interruption in the oil supply and the oil supply is again resumed, the said oil will fill the generator 21 and will pass upwardly through the gas outlet pipe 26 and through the burner nozzle 28. 75 The oil from the burner nozzle will then run through the flues 20 filling up the burner 12 and as soon as the level of oil reaches the wires 38 and 41, an electric circuit will be completed through the solenoid 33 and battery 80 40. The solenoid will then be energized whereby to cause the moving of the plunger 35 and the closing of the needle valve 24. From the foregoing, it will be appreciated 85 that there has been provided a novel and simplified oil burner which will accomplish all of the objects and perform all of the functions enumerated as being desirable in the statement of the invention set forth hereinabove and it is to be further understood 90 that changes in the details of the present invention may be resorted to without departing from or sacrificing the spirit of the invention so long as such changes fall within the scope of the appended claims. 95

What is claimed is:

1. A hydro-carbon burner of the character described, comprising an upright supporting standard having the surface of the upper portion thereof provided with a plurality of longitudinally extending flutes, a closed casing constituting a gas generating chamber and having a central passage-way formed therethrough to receive the fluted upper end of said standard for support of the casing thereon, oil supply means leading into said chamber, a gas lead-off pipe extending from the upper portion of said chamber to a position over the upper end of the passage therethrough, discharging downwardly thereover, 100 and a pre-heating igniting element arranged beneath the casing in such position as to permit a flame to pass upwardly through said passage along said flutes for the purpose of igniting the gas issuing from the discharge 105 end of said pipe.

2. A hydro-carbon burner of the character described, comprising an upright supporting standard having the surface of the upper portion thereof provided with a plurality of longitudinally extending flutes, a closed casing constituting a gas generating chamber and having a central passage-way formed therethrough to receive the fluted upper end of said standard for support of the casing thereon, oil supply means leading into said chamber, a gas lead-off pipe extending from the upper portion of said chamber to a position over the upper end of the passage therethrough, discharging downwardly thereover, 120 125 130

and a pre-heating igniting element arranged beneath the casing in such position as to permit a flame to pass upwardly through said passage along said flutes for the purpose of igniting the gas issuing from the discharge end of said pipe, said casing having the upper surface thereof of frusto-conical configura-

tion to provide sloping flame spreader walls for the burning gases issuing from the discharge end of said gas pipe.

In testimony whereof we affix our signatures.

FRANK ENGEL.
JULIUS ENGEL.
